UNITED STATES PATENT OFFICE.

JOHN SCHWECHLER, OF PHILADELPHIA, PENNSYLVANIA, ASSIGNOR OF SEVEN-EIGHTHHS TO PHILIP F. NASH, GEORGE W. LOCKREY, GEORGE DAVIS, WILLIAM R. MURPHY, AND FLOYD A. BRAERMAN, OF SAME PLACE, AND FRANK M. MARTIN, OF VENTNOR, AND EDWARD F. KLINE, OF ATLANTIC CITY, NEW JERSEY.

DESIGN FOR A PAVING-BLOCK.

SPECIFICATION forming part of Design No. 25,334, dated March 31, 1896.

Application filed February 13, 1896. Serial No. 579,180. Term of patent 14 years.

To all whom it may concern:

Be it known that I, JOHN SCHWECHLER, a citizen of the United States, residing in the city and county of Philadelphia, State of Pennsylvania, have invented and produced a new and original Design for a Paving-Block, of which the following is a specification, reference being had to the accompanying drawings, forming part thereof.

10 The leading feature of my design for a paving-block is a block having its sides with portions thereof inclined to each other, and its ends parallel and the edges of the top being chamfered.

15 Figure 1 represents an end elevation of a paving-block embodying my design. Fig. 2

represents a side elevation thereof. Fig. 3 represents a perspective view thereof. Fig. 4 represents a top or plan view thereof.

In the drawings, A designates a paving-block, having the sides D D of the upper body portion C inclined to the sides E E of the lower body portion B. The ends of the block are parallel in vertical direction and the edges of the top thereof are chamfered.

20 What I claim is—

25 The design for a paving-block, substantially as described and shown.

JOHN SCHWECHLER.
